UNITED STATES PATENT OFFICE.

JOHN R. ZEISER, OF BERWICK, PENNSYLVANIA.

MOLD.

1,092,622.

Specification of Letters Patent.

Patented Apr. 7, 1914.

Application filed April 9, 1912. Serial No. 689,489.

To all whom it may concern:

Be it known that I, JOHN R. ZEISER, a citizen of the United States, residing at Berwick, in the county of Columbia and State of Pennsylvania, have invented certain new and useful Improvements in Molds, of which the following is a specification.

This invention relates to mold forms for concrete side walks and more particularly to that type including side-bars which are connected by transversely arranged division-plates, and the invention has for its object to provide novel means for firmly connecting the said bars and division-plates. As ordinarily constructed, such forms have wedges inserted in the slots in the division-plates, which slots receive the side-bars, for the purpose of firmly bracing the connection between these elements. However, considerable trouble is involved and time spent in driving the wedges into place and removing them when the form is to be taken apart.

The present invention, therefore, aims to provide means which will automatically bind the connection between the division-plates and side-bars and which will be automatically released when the division-plates are lifted from the side-bars.

For a full understanding of the invention reference is to be had to the following description and accompanying drawing, in which:—

Figure 1 is a perspective view of a section of a sidewalk mold form embodying the present invention. Fig. 2 is a vertical transverse sectional view therethrough.

Corresponding and like parts are referred to in the following description and indicated in all the views of the accompanying drawing by the same reference characters.

In the drawing, the side-bars of the form are illustrated as of channel formation, their body portions being indicated by the numeral 1 and their upper and lower flanges by the numerals 2 and 3, respectively. These flanges extend laterally in horizontal planes, as shown in the drawing, and the flange 2 is of less width than the flange 3. At suitable intervals the body 1 and flange 2 of each side-bar is slotted as at 4 to receive the end-portions of the division-plate, as will be presently explained.

Each of the division-plates above referred to, is indicated by the numeral 5 and each

is formed with a slot having a vertical edge 6 and an edge 7 which is parallel to the wall 6 and extends from the lower end of the slot to a point below the upper end thereof. The slot is gradually decreased in width in the direction of its upper end as at 8 and at its extreme upper end is of a width equal to the thickness of the body of either side-bar.

By referring to Fig. 2 of the drawing, it will be observed that the division-plates are assembled with the side-bars of the mold form by fitting their ends upon the side-bars with their portions between the upper ends of the slots 6 and their upper edges inserted within the slots 4 in the side-bars, and with the vertical wall 6 of each slot resting against the inner side of that side-bar which it receives. The means provided for holding the division plates and side-bars firmly braced at their point of connection, is in the nature of a dog 9 pivoted at a point midway between its ends as at 10 to that portion of the division plate located between the wall 7 of the slot therein and the adjacent end-edge thereof. This dog 9 has parallel edge portions 11 and has its end-edges of cam formation as indicated at 12.

It will be noted from Fig. 2 of the drawing that the pivot 10 for the dog is located beyond a vertical line passing through the free edge of the upper flange 2 of the adjacent side-bar so that when the division-plate is lifted from engagement with the side-bars, the dogs carried thereby will strike against the flanges 2 and be rotated upon the pivots to assume a substantially vertical position, in which position they will clear the free edges of the said flanges 2. In a like manner, when the division-plates are being assembled with the side-bars, the dogs will be similarly turned in order to pass the flanges 2.

It will now be apparent from reference to Fig. 2 that when either edge 11 of each dog rests upon the flange 3, one end or the other of the dog will engage against the outer face of the body portion of the adjacent side-bar, and by reason of the peculiar contour of the end edges of the dogs, and also due to the fact that their engaging ends are located upon opposite sides of the longitudinal median line of the dog, that end which is in engagement with the body portion of the side-bar will be located below a horizontal line passing through the pivot 10.

In this manner the side-bars are firmly braced against outward movement of their lower portions when the concrete is poured into the form. It will be readily understood at this point that when the division plates 5 are set into place and when they are removed, the dogs carried thereby will be automatically swung upon their pivots so as to engage with the side-bars or disengage therefrom, and consequently the use of tools for the purpose of disassembling the division-plates from the side-bars, is rendered unnecessary.

Having thus described the invention what is claimed as new is:—

15. In a mold form of the class described, a side-bar, a division-plate fitted to the side-bar, and means mounted for turning movement upon the division-plate and bearing 20 against the side-bar and restraining the latter against outward movement, the means being arranged to automatically engage with and disengage from the side-bar when the division-plate is assembled therewith and 25 separated therefrom, respectively.
2. In a mold form of the class described, a side-bar, a division-plate fitted to the side-bar, and a dog pivoted upon the division plate and having oppositely located engaging 30 ends, either of said ends bearing against the side-bar and restraining the latter against outward movement, the side-bar having a portion arranged for engagement by one end of the dog whereby to cause automatic 35 engagement of the other or the same end of the dog with the side-bar when the division-plate is assembled therewith.
3. In a mold form of the class described, a side-bar, a division-plate fitted to the side-bar, the side-bar having a base-flange, and a dog pivoted upon the division-plate and having an engaging end bearing against the side-bar and restraining the latter against outward movement, the dog having a portion 40 arranged to engage with the flange when the division-plate is assembled with the side-bar whereby to direct the engaging

end of the dog into engagement with the side-bar.

4. A mold form of the class described, a 50 side-bar, a division-plate formed with a slot receiving the side-bar between its walls, one wall of the slot resting against one face of the side-bar, and a dog pivoted upon the division-plate at one side of the slot therein 55 and having an engaging end extending across the slot and bearing against the other face of the side-bar.

5. In a mold form of the class described, a 60 side-bar, a division-plate having a slot receiving the side-bar, and having one of its end walls resting against the face of the said side-bar, the side-bar having a base flange, and a dog pivoted upon the division-plate and having oppositely presented 65 engaging ends and parallel edges between the ends, one of said parallel edges resting upon the said base flange and one of the engaging ends bearing against the said side-bar and holding the same in position against the 70 wall of the slot.

6. In a mold form of the class described, a side-bar, a division-plate formed with a slot receiving the said side-bar, one wall of the slot bearing against one side of the bar 75 and the other wall being spaced therefrom, a dog pivoted upon the division-plate, the dog having oppositely presented engaging ends of cam formation, the said ends being located at opposite sides of the longitudinal 80 median line of the dog and the body of the dog between its said ends having parallel edges, the side-bar being formed with a base-flange and the dog having one of its parallel edges resting upon the upper side of the 85 flange and one of its ends engaging against the side-bar whereby to hold the same against the first mentioned wall of the slot.

In testimony whereof I affix my signature in presence of two witnesses.

JOHN R. ZEISER. [L. s.]
